UNITED STATES PATENT OFFICE.

FIRM B. BYERS, OF NEW YORK, N. Y.

COLLAR AND NECKTIE HOLDER.

1,392,298.

Specification of Letters Patent.

Patented Oct. 4, 1921.

Application filed March 19, 1920. Serial No. 367,100.

To all whom it may concern:

Be it known that I, FIRM B. BYERS, a citizen of the United States, residing at New York city, in the county of New York and State of New York, have invented certain new and useful Improvements in Collar and Necktie Holders, of which the following is a specification.

This invention is in the nature of a holder for collars and neckties, and especially soft collars, being adapted to clasp and hold the ends or flaps of said collars, and the invention consists in the improved construction hereinafter described and afterward specifically claimed.

In order that the invention may be readily understood, I will now proceed to describe its construction and operation in connection with the accompanying drawing, in which:

20 Figure 1 represents, in top plan view, a fastener constructed in accordance with my invention, by being stamped or cut out of sheet metal by suitable dies;

25 Fig. 2, a similar view of a modified form thereof;

Fig. 3, a similar view of a further modification; and

30 Fig. 4, a similar view of a further modification, showing in dotted lines, a cut-off necktie in position in the fastener.

Like reference characters mark the same parts in all the figures of the drawing.

Referring specifically to the drawing, 1 indicates the front bar, curved as shown and thickened on its inner ends at 2 and 3.

40 Formed on and projecting inward from the inner side of the front bar 1, at each side of the center thereof, is an inwardly inclined arm, as at 4 and 5, each formed with an inwardly turned hook-like end as 6, 7, the said ends being curved and located opposite the thickened portions 2 and 3, the elasticity of the front bar 1 and of the hook-like ends 6 and 7 serving to clasp the edges of a collar projected between these parts.

45 In Fig. 2, the modification consists in thickening the ends of the arms 4 and 5, as at 8 and 9, opposite the thickened ends 2 and 3 of the front bar, so that, by the elasticity of the front bar, and the arms 4 and 5, the edges of the collar are clasped between the thickened portions 2, 3, and 8, 9.

50 In Fig. 3, the modification from the construction of Fig. 1 is slight, the hooked portions 10, 11, being sharpened at the ends as at 12 and turned more abruptly to bring

them opposite the thickened ends 2, 3, of the curved front bar 1, the hooked ends being shorter than those of Fig. 1, and the space between the points of attachment of the arms 60 4 and 5 with the front bar being farther apart and farther from the center of the front bar.

In the construction shown in Fig. 4, the curved bar 1 is modified, the central portion 65 13 being substantially semi-circular, with the ends 14, 15 turned and curved in the opposite direction, the semi-circular part receiving a necktie 16, and provided with projecting arms 17, 18, curved oppositely to the parts 70 14 and 15 and provided with thickened portions 19, 20 opposite the thickened portions of the ends 14 and 15, the elasticity of the parts 14 and 15, and 17 and 18 serving to clasp the edges of the collar between their 75 thickened portions.

While it will be observed that in the foregoing description and in the accompanying drawings the various modifications of my invention are described and illustrated as 80 formed with thickened portions at the points where the holder engages and clasps a collar, it must be understood that the holder can be constructed without these thickened portions being provided and that as thus 85 constructed it will not depart from the principle covered by my invention.

Having thus fully described the construction and operation of my invention, what I claim as new and desire to secure by Letters Patent of the United States is:

1. A collar and necktie fastener comprising a front curved bar thickened at its outer ends, and elastic arms projected from the inner face of said front bar and forming, 95 with said thickened ends, clasps for the edges of a collar, said elastic arms being bent back at their ends opposite said thickened portions of the front curved bar, and the bends being sharpened to facilitate their 100 engagement with the collar.

2. A collar and necktie fastener struck from sheet metal having one bar provided with a central semi-circular portion to receive a necktie and elastic clasping ends for 105 the edges of the collar.

3. A collar and necktie fastener struck from sheet metal having one bar provided with a central semi-circular portion to receive a necktie and elastic clasping ends for 110 the edges of the collar, the outer front ends of the bar being curved in the opposite di-

rection from the curve of the semi-circular portion, and oppositely curved arms extending from the semi-circle, the curves being opposite to those of the outer ends of the 5 front bar.

4. A collar and necktie fastener struck from sheet metal having one bar provided with a central semi-circular portion to receive a necktie and elastic clasping ends for 10 the edges of the collar, the outer front ends of the bar being curved in the opposite direction from the curve of the semi-circular portion, and oppositely curved arms extending from the semi-circle, the curves being opposite to those of the outer ends of the 15 front bar, and these parts having thickened ends to clasp the collar.

5. A device of the character set forth, comprising a central open loop portion adapted 20 to partly inclose a necktie, and resilient end portions projecting from the central portion adapted to engage the edges of a collar.

6. A device of the character set forth,

comprising a central open loop portion 25 adapted to partly inclose a necktie, and resilient end portions each comprising a pair of arms projecting endwise from the central portion with their opposed edges near the ends located adjacent to engage the edges of the collar.

7. A device of the character set forth, comprising a central open loop portion 30 adapted to partly inclose a necktie, and resilient integral end portions projecting from the central portion adapted to engage the edges of a collar.

8. A device of the character set forth, comprising a central open loop portion 40 adapted to partly inclose the necktie, and resilient integral end portions each comprising a pair of arms projecting endwise from the central portion with their opposed edges near the ends located adjacent to engage the edges of the collar.

In testimony whereof I affix my signature. 45

FIRM B. BYERS.
